UNITED STATES PATENT OFFICE.

ISRAEL E. ROSENTHAL, OF ARGENTA, ARKANSAS.

SAFEGUARD LIFE AND TELEPHONE ATTACHMENT.

113,052.

Specification of Letters Patent.

Patented Oct. 6, 1914.

Application filed February 27, 1913. Serial No. 751,005.

To all whom it may concern:

Be it known that I, ISRAEL E. ROSENTHAL, a citizen of Argenta, in the county of Pulaski and State of Arkansas, have invented a new and useful Improvement in Safeguard Life and Telephone Attachments, of which the following is a specification.

My invention is an improvement in safe guard life and telephone attachments, and has for its object the provision of mechanism for installation in homes, hospitals, factories, ware-houses, and the like, for protecting and safe guarding lives and property in case of fire, wherein means is provided for automatically sounding an alarm and at a time before the fire has gained too great a headway to be extinguished.

In the drawings:—Figure 1 is a perspective view of the improved attachment, Fig. 2 is a section on the line 2—2 of Fig. 1, Fig. 3 is a section on the line 3—3 of Fig. 2, Fig. 4 is a perspective view of the signal device with the parts separated, Fig. 5 is a transverse section of the fuse attachment, and Fig. 6 is a section on the line 6—6 of Fig. 5.

The present embodiment of the invention is adapted to be arranged near a telephone transmitter 1, immediately below the hook 2, that supports the receiver 3, and the said device comprises a casing 4, having at its rear an upward extension 5, in which is arranged a guideway 6 at the rear thereof, the said guideway being reinforced by a channel plate 7, whose side edges are laterally flanged at 8, and are seated in counter-sinks, and secured to the extension and the casing by screws 9, or the like. The said guideway is at the rear of the casing and extends the full height of the extension and a portion of the height of the body of the casing. A slide or sliding member 10 is mounted in the guideway, and at approximately the center of the guideway the reinforcement 7 is provided with a lug 11, extending into the guideway, the said lug being rectangular in cross section and having a threaded opening 12. The sliding member 10 is longitudinally slotted at 13 and 14, the latter slot or recess receiving the lug 11.

Above the slot or recess 13, the sliding member is recessed at its opposite side edges as indicated at 14, and just above the said recesses and above the upper end of the bar 15, the sliding member is provided with a cross bar 15, connected to the sliding member by

arms 16. The lower end of the sliding member is provided with oppositely arranged parallel depending lugs or arms 17, and each lug or arm is provided on its rear face with a projection 18.

The sliding member is, as before stated, arranged in the guideway, and the side walls of the guideway are provided with inwardly extending longitudinal ribs 19, the said ribs engaging behind the sliding member to retain the same in place in the guideway. A cover plate 20 is arranged over the guideway, and the said plate is held in place by a screw 21, which passes through an opening in the cover plate and engages the opening of the lug 11.

A coil spring 22 is arranged between the lug 11 and the lower end of the slot or recess 14, the said spring acting normally to pull the sliding member upward. The sliding member is normally held in the position of Fig. 2 with the cross bar above the upper end of the extension 5, by means of a latch or trip in the form of a sleeve or button 23, having each of its ends enlarged at 24 and 25 respectively, the latter forming a head for engagement by a striker, to be presently described, to release the sliding member.

The trip or latch is normally pressed toward the front wall of the casing 4, by means of a coil spring 26, the said spring being arranged between the cover plate 21 and the head 25 of the trip, a portion of the spring being within the body of the trip. The trip or latch passes through an opening 27 in the reinforcing member 7, and the head 25 is in the body of the casing 4, near the top thereof. The said reinforcing member 7 is extended below the extension, as will be seen from an inspection of Fig. 2, and the enlargement 24 of the trip is in the shape of a cross head whose ends engage above the projections 18 on the lugs 17 to hold the sliding member in lowered position.

The striker, before mentioned, comprises an angular head or hammer 28, on the upper end of a lever 29, which is pivoted at 30, to a bracket arm 31, in the lower end of the casing 4. A spring 32 is arranged at the lower end of the lever below the pivotal connection 30 thereof and the said spring normally acts to move the hammer or head away from the trip or latch, before mentioned. The tension of the spring 32 may be adjusted by means of a set screw 33, threaded through a bracket 34 on the bot-

tom of the casing and engaging the spring at its inner end.

A lock nut 35 is provided for holding the screw in adjusted position. The outward movement of the upper end of the lever is limited by means of a set screw 36, threaded through an angular lug 37 on a bracket 38, secured to the rear wall of the casing and extending forwardly therefrom, and a lock nut 39 is provided for holding the screw in adjusted position.

A magnet or magnets 40 are supported by the bracket 38, before mentioned, and the cores of the magnets act upon an armature 41, secured to the lever 29, transversely thereof. A signal in the form of a bell 42 is mounted on the front of the casing on a base 43, secured to the casing, and the bell is an electric bell interposed in the circuit 20 of the magnets 40 and arranged to sound when the circuit is completed through the magnets. The magnets are in circuit with the fuse attachments shown in detail in Figs. 5 and 6, and the said attachments may be arranged wherever desired throughout the building, as for instance, one of the said attachments may be mounted in each room of the building, or as many may be used as thought advisable. Each of the said attachments 30 comprises a casing of cylindrical shape, consisting of a base or bottom 44, and the cover 45, the cover fitting over the base as shown more particularly in Fig. 6. Binding posts 46 are connected with the opposite sides of the box as shown in Fig. 5, each binding post having a stem 47, passing through an opening in an internal boss 48, on the base or body and the inner end of each stem is headed as shown at 49 to hold 40 the binding post in place.

A resilient strip is connected with each binding post, each of the said strips 50 having an angular portion 51, held between the face of the boss 48 and the head 49, and the said strips extend approximately diametrically of the box and are held in spaced relation by means of a fusible block or plate 52. The said block or plate may be of any suitable material, as for instance, wax 50 position, and is of sufficient thickness to space the strips apart normally, but of sufficient thinness to be melted by a small amount of heat.

Lead wires 53 and 54 are connected with the binding posts and the said lead wires are connected with binding posts 55 on the front face of the casing 4 at the lower end thereof, but one of the said posts being shown. A suitable source of electrical energy 56 is interposed in the circuit, to supply current, and the said source may be of any desired kind, as for instance, dry cells, properly connected. The strips 50 are the terminals of the said circuit, and as long as 65 the plate 52 is in place between the free

ends of the said strips, the circuit will be open. As soon, however, as the plate is melted or fused the strips will contact and the circuit through the magnets and the signal 42 will be closed. The fusible attachments 70 may be arranged wherever desired, preferably in inconspicuous positions and they are so arranged that in case of fire, they will be soon acted upon by the heat.

In operation, whenever sufficient heat is 75 generated in the neighborhood of one of the attachments shown in Figs. 5 and 6, the plate or block 52 will be fused and the free ends of the strips 50 will contact, thus completing the circuit through the magnets 40 80 and through the signal 42. As soon as the circuit is completed, the signal sounds and the striker is drawn toward the trip or latch 23, and strikes the said trip or latch, moving it toward the rear of the casing 4, thus causing the cross head 24 to release the projections 18 and the sliding member is pushed 85 upward by the spring.

The casing 4 is arranged as before stated, adjacent to a telephone transmitter, and 90 in such position that the cross bar 15 is directly below the hook 2 that supports the transmitter 3. As soon as the sliding member is released, the spring 22 forces the said member upward and the cross bar 15 engages the hook 2, lifting the same, and the central office is notified of the conflagration.

The device may be used in connection with an ordinary telephone transmitter, so that no additional wires are required leading 100 from the building to be protected to the place where the alarm is to be sounded. The only wiring that is necessary is that in the building to be protected. The fusible attachments constructed as shown must be 105 arranged in parallel in the circuit.

The casing 4 and the extension 5 are provided at one side edge and on their rear faces with laterally extending perforated lugs 57, for receiving screws 58 or the like to 110 connect the device with the wall that supports the transmitter. The front of the casing is also provided with similar lugs 57 for the same purpose.

I claim:

A device for engaging the hook of a telephone transmitter to move the same to sound an alarm, comprising a casing adapted to be arranged beneath the hook and having a vertical guideway opening below the hook, a slide movable in the guideway and adapted to engage the hook at its upper end, a trip for holding the slide in lowered position, a spring acting normally to move the slide upward into normally to move the slide upward into engagement with the hook, a spring normally holding the trip in engagement with the slide, a striker within the casing, said striker being pivoted at one end and being mounted, 130

to swing toward and from the trip and having at its upper end an angular arm for engaging the trip to trip the same when the striker is swung toward the trip, a magnet for moving the striker toward the trip, an open electrical circuit in which the magnet is interposed, said circuit being adapted to

be closed to energize the magnet, and a spring acting normally to move the striker away from the trip.

ISRAEL E. ROSENTHAL.
